UNITED STATES PATENT OFFICE.

FRANCIS W. GIBSON, OF WEST ROXBURY, MASSACHUSETTS.

SIGNBOARD.

1,342,538.

Specification of Letters Patent.

Patented June 8, 1920.

Application filed January 8, 1919. Serial No. 270,201.

To all whom it may concern:

Be it known that I, FRANCIS W. GIBSON, a citizen of the United States, residing at West Roxbury, county of Suffolk, Commonwealth of Massachusetts, have invented certain new and useful Improvements in Signboards, of which the following is a specification.

This invention relates to sign boards and particularly to advertising display boards for use along highways and other places where there is passing traffic desired to be reached by advertising matter.

The usual type of display board has been open to various objections. First of all, unless built in a very substantial manner at a correspondingly high cost, it is liable to be blown down or destroyed by wind, and in the second place, owing to long use it has lost effectiveness in attracting attention because of its too familiar nature. The possibilities of advertising of this type, however, are still great, and various efforts have been made to revive roadside advertising and restore its waning power of arresting attention.

To the end therefore of producing such an improvement in the art I have devised my present invention. In this I overcome the expense of heavy permanent structure by making the sign automatically "head" into the wind and thus avoid lateral pressure, which at once relieves the necessity of heavy and expensive structure and adds a desirable factor of arresting attention. This increased power of arresting attention comes from the fact that the apparent position of the sign relative to the passing traffic varies from time to time with the shift of the wind so that a sign which was observed in the morning and which if in the same position might fail to arrest attention in the afternoon, would immediately become conspicuous on account of its change of position in the landscape. Furthermore any sign fixed relative to the roadway has only an average visibility to the passing public due to angle of approach, eye sight and speed of passing. A sign, however, which varies in position from day to day, perhaps hour to hour, increases the average of its visibility by reaching individuals within whose range it otherwise would not come.

The above features, as well as certain other elements of novelty, are embodied in

my invention as will be hereafter explained and are illustrated in the embodiments shown in the accompanying drawings. Throughout the specification and drawings, like reference numerals are employed to indicate corresponding parts. In the drawings:

Figure 1 is an elevation partly in section of a board in accordance with my invention.

Fig. 2 a plan view of the same.

Fig. 3 a sectional detail of the bearing.

Fig. 4 is a transverse section of a further modification.

Fig. 5 is a detail view of a portion of one of the ornamental side frame members of the sign unit shown in Fig. 4.

Fig. 6 is a transverse section of a sign unit modified for illumination, and Fig. 7 is a detail section illustrating a form of supporting member.

In carrying out my invention I provide a vertical supporting member or post 1 which may be conveniently made of pipe or tubing and which is preferably set with cross pins 2 in a cement base 3. It is to be borne in mind that many of the choicest locations for sign boards are in land under cultivation or at least in grass, where the setting of a large number of posts and braces is objectionable to the owner of the land and frequently involves considerable adjustment for land renters at present. My single post therefore constitutes a feature of great practical importance in locating signs in desirable spots without interfering with the cultivation of the adjacent area or with any serious obstruction of light or accessibility.

For greater rigidity of structure and convenience of assembly, the tubular support 1 may be sectional, and the sections united by any suitable coupling 20, a smaller tube 21 being embedded in the base 3 within the sectional support 1.

Hung on the upright 1 is an advertising carrying member 4 which is preferably formed by a plurality of suitably shaped horizontal frame pieces 5 revolvably supported on the upright 1 and covered externally by sheets 6-6 of fiber board or the like. The pieces 5 are tapered toward each end so that the sheets 6-6 come together at vertical lateral edges which are bound by U-shaped strips 7 at each end thereof to prevent any working loose of the covering material and makes of the member 4

a clean wind resistant structure. The sheets 6—6 may be directly lithographed or any desired advertising matter may be printed or pasted thereon.

5 The member 4 may be either a simple rectangular member or may be contoured or outlined to give more striking effect. Where contour effect is provided, shorter cross pieces may be employed as indicated at 5¹, 10 Fig. 1. These cross pieces 5¹ may be of a variety of lengths so as to give support to the member at a reasonable number of points. It is to be borne in mind, however, that inasmuch as my sign keeps itself headed into the wind, very little wind pressure is encountered and such pressure as there is comes edgewise against the tapered edges of the sign. The structure may therefore be very light and of a cheaply produced 20 nature.

The member 4 is preferably hung on a free bearing which in the form shown is conveniently made by setting into the upper frame 5 a cup-shaped piece 6¹ having 25 flanges 7 which bear on the under side of the piece 5 and be there held by screws 8. The upright 1 as shown in Fig. 2 preferably has a plug 10 in which is a central vertical bolt opening for receiving a bolt 11. 30 On top of the plug 10 is formed a hemispherical bearing portion 12 suitably treated as by soaking in oil so as to form an easy bearing substantially conforming to the cup-shaped socket 6¹ but allowing room 35 for play and for takeup in wear. The upper end of the tubular support 1 with the opposing bottom of the socket 6¹ constitutes a limiting paid in case of looseness or wear in the bearing. The shank of the 40 bolt 11 is threaded and a nut 13 and lock nut 13¹ run down adjacent the top of the cup 6¹ to hold the sign from lifting to any undesirable extent on the upright. Above the nut 13, preferably clamped by another 45 nut, 14, is a fixed pointer 15 indicating direction or distance. I furthermore contemplate topping the uprights with cross arms 16 indicating the points of the compass. This adds to the interest of the sign not 50 only supplying information as to the compass points to the passing public, but in connection with the sign itself, giving indication of direction of the wind as a further added interest to the sign.

55 The support 1 for the sign unit is disposed to one side of the vertical axis of the sign so that the sign will automatically head into the wind, but will not spin about the support as an axis. The sheets 6—6 each 60 provides a surface for the display of advertising matter, and by reason of the capacity for rotation, the effective advertisement-bearing area of the sign relative to the road or other way is thus doubled.

65 In Fig. 4, the horizontal struts or cross

members 5 are recessed at their ends, as indicated at 26, to receive lateral frame members 27, which may be of any desired ornamental form, as the arrow-configuration illustrated. The members 27 are 70 formed to provide surfaces 28 to which the sheets 6—6 may be tacked.

In Fig. 6, an illuminated sign unit is shown. In such a sign, the letters or other indicia to be displayed may be cut through 75 the sheets, as indicated at 30. The incandescent bulb or other light source 31 may be conveniently supported upon one of the transverse web members 5, and the feed wires may be introduced through the hole 80 low support 1.

Signs in accordance with my invention in addition to having a very high degree of appeal have a high potential utility in their relation to sign board erection and maintenance. The small amount of space that is required of the land owner frequently makes possible the securing of desirable locations otherwise unattainable, so that favorable arrangements may be made in locating the 90 boards. The swinging movement of the sign furthermore not only so far reduces interference with growing crops as to eliminate objection on that score, but is even a protection to crops as in case of corn or 95 other grains. In such location the sign acts as a "scare crow" and performs the function of making the sign welcome instead of unwelcome to the farmer.

All the above suggested and various other 100 modifications may obviously be made in carrying out this invention, in detail of structure and form of sign used, all without departing from the spirit of my invention if within the limits of the appended claims. 105

What I therefore claim and desire to secure by Letters Patent is:

1. In a roadside sign board, a sign unit comprising a fixed vertical support, spaced horizontal frame members eccentrically 110 mounted on said support and oscillatable thereabout as an axis, and oppositely arranged surfacing members vertically connecting said frame members and inclosing said support.

2. In a roadside sign board, a sign unit comprising a fixed vertical support, spaced horizontal frame members eccentrically mounted on said support and oscillatable thereabout as an axis, a pair of oppositely 120 curved surfacing members vertically connecting said frame members and inclosing said support, and a relatively stationary direction indicator mounted upon said support.

3. In a roadside sign board, a sign unit comprising a fixed vertical support, longitudinally tapered frame members eccentrically mounted on said support in spaced horizontal relation thereto and oscillatable 130

thereabout as an axis, and opposed display surfaces of similar convexity attached to and connecting the opposite longitudinal edges of said frame members.

5 4. In a roadside sign board, a sign unit comprising a fixed vertical support, tapered frame members eccentrically mounted on said support in spaced horizontal relation thereto and oscillatable thereabout as an axis, a pair of oppositely arranged display members of similar convexity attached to and connecting said frame members, and wind resistant finishing strips vertically connecting the meeting edges of said display members.

10 5. In a sign board, a sign unit comprising a fixed support, and a display member eccentrically mounted on said support for limited oscillation thereabout as an axis through an arc of not more than 180° in either direction.

20 6. A roadside sign board comprising a fixed vertical tubular supporting member,

lateral frame pieces, a bearing plug lodged within the upper end of said tubular member and having a bearing formed at its upper end, a bearing socket on a frame piece laterally of the center thereof and a spindle fixed in said lug and extending through said bearing and socket, and a surfacing attached to said frame members thereof and inclosing said vertical support. 25

7. In a sign board, a sign comprising a base, and a sectional tubular support, a coupling connecting said tube sections, a tube 35 of smaller diameter embedded in said base within said sectional tube, and a sign element mounted on said sectional tube for movement thereabout as an axis.

In testimony whereof I affix my signature 40 in presence of two witnesses.

FRANCIS W. GIBSON.
